Charles Smith, Inventor
C. Snowdon

UNITED STATES PATENT OFFICE.

CHARLES SMITH, OF ROGERS, ARKANSAS.

HOOK.

SPECIFICATION forming part of Letters Patent No. 400,501, dated April 2, 1889.

Application filed December 29, 1888. Serial No. 294,920. (No model.)

To all whom it may concern:

Be it known that I, CHARLES SMITH, a citizen of the United States, residing at Rogers, in the county of Benton and State of Arkansas, have invented a new and useful Improvement in Snap-Hooks, of which the following is a specification.

My invention relates to an improvement in snap-hooks to be used for securing halter-straps, check-lines, breast-straps, or other parts of a harness, and for other analogous purposes; and it consists in the peculiar construction and combination of devices that will be more fully set forth hereinafter, and particularly pointed out in the claims.

In the drawings, Figure 1 is a perspective view of the obverse side of a snap-hook embodying my improvements. Fig. 2 is a similar view of the reverse side of the same, showing the hook in dotted lines, swung to a position to admit of the disengagement of the link or ring. Fig. 3 is a sectional view of my improved snap-hook.

A represents a circular guard-disk, and B represents the shank which projects therefrom, and is provided at its outer end with a transverse slot, C, adapted for the attachment of one end of a strap, in the usual manner. Said disk or guard and said shank are formed integrally of a single piece of metal, which may be either cast, wrought, or stamped. The shank B has at its inner end an offset or shoulder, D, which connects it with the guard-disk, the said shank being thereby arranged parallel with but in a different plane from the guard-disk. The latter has in that portion of its periphery which is under the shank a crescent-shaped notch, E, the radius of which will in a measure be governed by the size of the ring or link F.

G represents a hook, which has its inner end pivoted under the center of the guard-disk by means of a bolt, H. A washer, I, is interposed between the head of the bolt and the hook, and a nut or washer, K, is screwed or swaged on the opposite end of the bolt and bears against the center of the guard-disk. The point of the hook bears upon the upper side of the guard-disk, and said hook is adapted to be swung to any desired position on the pivotal bolt.

In order to attach the ring or link F to the hook, or to disconnect the same therefrom, the hook must be swung to a position under the shank B in order to clear its point of the

guard-disk, as illustrated in dotted lines in Figs. 2 and 3.

A snap-hook thus constructed is cheap and simple, is very strong and durable, and is so arranged that it is almost impossible for the ring or link to become accidentally detached from the hook, owing to the fact that the latter must be swung to a position under the shank and directly registering with the notch in the disk, and to the further fact that the ring or link must be swung over the point of the hook at the instant that the latter is in this position before it can become disengaged.

I am aware of the Patent No. 86,188, granted January 26, 1869, in which is shown a hook pivoted to a plate, the latter being provided with a notch, so that when the hook aligns with the notch the device can be released; but in this patent the notch is provided on one side; and, furthermore, the point of the hook does not bear on the plate. In my invention the notch in the disk is provided at the inner end, so that there is no possibility of the ring F being detached.

Having thus described my invention, I claim—

1. The snap-hook comprising the circular disk A, having the notch E in one side, the shank B, projecting from the disk and having the offset or shoulder D at its inner end attached to the disk at the notched portion thereof, whereby the said shank extends over the notch and is in a different plane from the disk, and the hook G, having its inner end pivoted to the center of the disk, the point of the hook being adapted to sweep on and in contact with the disk until it reaches the notch E, substantially as described.

2. The snap-hook comprising the circular disk A and the integral shank B, said disk having the notch E in one side, and said shank having the offset or shoulder D and being arranged over the notch, and the hook G, having its inner end pivoted under the center of the disk, and having its point adapted to sweep on and in contact with the disk until it reaches the notch E, substantially as described.

In testimony that I claim the foregoing as my own I have hereto affixed my signature in presence of two witnesses.

Witnesses: CHARLES SMITH.
